FIG. 1

FIG. 5

FIG. 2

FIG. 6

FIG. 3

FIG. 7

FIG. 4

FIG. 8

FIG. 1 is a top plan view of a digital wristwatch illustrating my new design, and showing a typical time display;

FIG. 2 is a right side elevational view thereof;

FIG. 3 is a left side elevational view thereof;

FIG. 4 is a top, front, and right side perspective view thereof showing a typical time display;

FIG. 5 is a front elevational view of another embodiment of my new design of FIG. 1 wherein a typical calendar display has been added to the front surface, all other views being identical to FIGS. 1-4;

FIG. 6 is a right side elevational view of yet another embodiment of my new design of FIG. 1 wherein the top surfaces are slightly convex and the stem is on the case-break line;

FIG. 7 is a left side elevational view of FIG. 6; and

FIG. 8 is top, front, and right side perspective views of FIGS. 6-7 showing a typical full-width time display.

The watchband, shown broken away in all figures, is conventional; and the bottom surfaces, not shown, are plain and unornamented.

I claim:

The ornamental design for a digital wristwatch, substantially as shown and described.
